Application September 21, 1948, Serial No. 148,686

Term of patent 14 years

(Cl. D58—9)

To all whom it may concern:

Be it known that we, Louis T. Schiavon and Benjamin A. Bauer, citizens of the United States, residing at the city of Watsonville, in the county of Santa Cruz and State of California, have invented a new, original, and ornamental Design for a Barrel Bottle, of which the following is a specification, reference being had to the accompanying drawing, forming a part hereof.

Fig. 1 is a front elevational view of a barrel bottle, showing our new design.

Fig. 2 is a side elevational view of Fig. 1.

Fig. 3 is a top view of Fig. 1, and

Fig. 4 is a bottom view of Fig. 1.

We claim:

The ornamental design for a barrel bottle, substantially as shown.

LOUIS T. SCHIAVON.
BENJAMIN A. BAUER.
